(57) **CLAIM**

The ornamental design for a melting pot, as shown and described.

DESCRIPTION

FIG. 1 is a top, rear and left-side perspective view showing my new melting pot design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is a top, rear and left-side perspective view showing my new melting pot design with the thermometer thereof separated from the rest of the melting pot.

The broken lines depict portions of the melting pot that form no part of the claimed design; the broken lines form no part of the claimed design.

1 Claim, 8 Drawing Sheets
